Term of patent 14 years

(Cl. D58—2)

FIG. 1

FIG. 2

FIG. 1 is a top perspective view of a packaged watch embodying our new design.

FIG. 2 is a side elevational view thereof.

The dominant features of our design reside in the portions shown in full lines and particularly in the combination of a caricaturized representation of a girl on one side of the top surface and a transparent window on the other half of the top surface of a package all as shown.

We claim:

The ornamental design for a packaged watch, as shown and described.
